VENETIAN BLIND

Bert N. Parmenter, Lake Forest, Ill.

Application July 28, 1934, Serial No. 737,346

18 Claims. (Cl. 156—17)

The present invention relates to Venetian blinds or shades and the like.

Among the objects of the invention is to provide a novel Venetian blind so constructed and arranged as to be contracted and extended in sections.

In the usual type of Venetian blind, the means, usually ropes, for raising or contracting the blind are connected to the lowermost or bottom slat 0 of the series of slats of which the blind is composed, so that upon pulling on the ropes the bottom slat is first raised until it contacts the next slat above which is then raised until it contacts the next slat above it and so forth. 5 In other words the slats pack or pile up from the lower end of the blind. Accordingly when the blind is raised part way, as for example, half way up, the packed or piled slats form a thick and unsightly pack or pile which cuts off 10 considerable light and air.

It is, therefore, an object of the invention to provide novel means, such as ropes, so constructed, arranged and connected to given slats of the series of slats of the blind as to start 15 packing or piling an upper group of slats instead of at the lower end of the blind so that as the upper group of the slats are packed or piled up, the lower portion of the blind will be raised with the slats in spaced relation. As for example, if the upper half of the slat series be 20 packed or piled up, the lower half will be raised half way up without any packing or piling up of the slats thereof, the lower slat coming at about the meeting rails of the upper and lower 25 sashes or casements of the window. In this way there is no unsightly and thick pack or pile of slats at that point. The ropes are so arranged and connected, when it is desired to raise the blind further, as to then start packing or piling 30 up the slats of the lower section. If the blind be composed in two sections, the latter packing or piling up will start at the bottom of the second section, that is, the bottom of the blind. If the blind be composed of three sections, the packing 35 up will start at the bottom of the second section, the third section being raised with the slats in spaced relation, and after the slats of the second section are all packed or piled up, then the packing or piling up of the slats of the third or lowest section will start. The same 40 system is used for four or more sections, it being understood the invention comprehends the providing of any number of sections desired.

The invention has as a further object of the invention the provision of a novel means for

supporting the suspending tapes of the blind and for tipping the slats to the desired inclination or horizontalwise. The usual ropes for tipping the slats are or may be eliminated.

A further object of the invention is to provide a novel support at the upper end of the blind. The usual type of support comprises a thick heavy cross-piece secured at its ends to the window frame and carrying pivot brackets for pivotally supporting beneath it another thick 5 heavy slat shorter in length than the cross piece. These are very unsightly and ugly. The present invention comprehends the provision of means which avoids these disadvantages, besides providing for a support which is simple in structure, 10 and very conveniently set in place.

Other objects, capabilities, advantages, features and the like are comprehended by the invention as will later appear and as are inherently possessed by the invention.

Fig. 1 is a front elevation of a Venetian blind 20 constructed in accordance with the invention;

Figs. 2 and 3 are similar views on a smaller scale, showing the blind at different stages of contraction of the blind;

Fig. 4 is a schematic perspective view showing 25 the rope system used in this invention for a two section blind;

Fig. 5 is a horizontal sectional view taken in a plane represented by line 5—5 in Fig. 1 of the 30 drawings;

Fig. 6 is a vertical sectional view taken in a plane represented by line 6—6 in Fig. 5 of the drawings;

Figs. 7, 8 and 9 are transverse vertical sectional views taken in a plane represented by line 7—7 in Fig. 1 of the drawings, and showing 35 different positions of the slats;

Fig. 10 is a perspective view of a cleat connected to the ends of the ropes for the upper 40 section or sections of the blind;

Fig. 11 is a perspective view of a form of supporting brackets used at the ends of the supporting member at the top of the blind, these brackets being securable to the inner facings of 45 the window jambs;

Fig. 12 is a similar view of a form of bracket for securing to the outer facing of the window jambs;

Fig. 13 is a schematic front perspective view 50 of a blind having three sections, showing the rope system therefor;

Fig. 14 is a top plan view of the same on a larger scale;

Fig. 15 is a schematic perspective view of a blind 55

having three sections and showing an alternate rope system therefor;

Fig. 16 is a similar view showing a further alternate rope system;

Fig. 17 is a top plan view of the supporting or head bar, showing an alternate form of supporting brackets; and,

Fig. 18 is a view in elevation of the same, with parts shown in broken section.

Referring more in detail to the drawings the embodiment selected to illustrate the invention is shown in connection with a window comprising side frame parts or jambs 1 and 2 to the inner facings of which are secured sash or casement stops or guide pieces 3 and 4, a stool 5, and a lintel stop 6.

The blind comprises a series of slats 7 of which the base slat 8 is heavier and thicker than the remaining slats of the series. The slats 7 are supported upon cross tapes 9 and 10 (Figs. 6, 7, 8 and 9) the ends of which are woven in or sewed to the suspending tapes 11 and 12, the cross tapes being in staggered relation for the successive slats so as to distribute the weight of the aggregate evenly on the suspending tapes instead of along an edge portion of each suspending tape. The lower end portions 13 and 14 of the suspending tapes pass under and support the base slat 8. The upper end portions 15 and 16 of the suspending tapes pass over hollow cylinders 17 and 18 which are rotatable on a supporting cross piece 19 which in this case is a square tube, the inner surfaces of the cylinders 17 and 18 bearing on the corners 20, 21, 22 and 23 (Figs. 7, 8 and 9) with only such friction as is necessary for the cylinders to remain in position after turning when tipping the slats or bringing them to horizontal positions.

Near the ends of the tube 19 are provided in the lower wall 24 thereof cross slots or openings 25 and 26 (Figs. 5 and 6), leaving cross bars 27 and 28 adapted to rest in brackets 29 and 30 secured to the inner facings of the window jambs. Intermediate the ends of the tube 19 the lower wall is also provided with openings 31 and 32 (Figs. 5 and 6) through which the ropes pass to the slats. At suitable points there are connected to and between the side walls 33 and 34 (Fig. 6) of the tube 19, tubes 35, 36 and 37 over which the ropes slide and turn as is clear from Figs. 5 and 6.

The cylinders 17 and 18 are provided with arc slots 38 and 39 of sufficient length to permit the cylinders to turn when the slats are tilted in either direction, so as not to interfere with the rope passing through the openings 31 and 32 of the support 19 and the slots 38 and 39 in the cylinders 17 and 18. At the upper part of the cylinders 17 and 18 are struck up ears 40, 41, 42 and 43 which may have apertures if desired for the passage of thread 44, 45, 46 and 47 sewed to the upper end portions of the suspending tapes 11 and 12, these tapes being thus secured to the cylinders so that they will not crawl and throw the arc slots 38 and 39 out of proper angular relation to the ropes passing therethrough.

The supporting brackets 29 and 30 shown in Figs. 5 and 6 are of the form shown more in detail in Fig. 11. Each of these brackets comprises a wall plate 48 which is secured to the inner facing of the window jamb or the stop 3 or 4 thereon, by any suitable elements, such as screws 49 (Fig. 5) passing through holes 50 provided in the plate 48, these holes being so located as to clear the ends of the side walls 33 and 34 of the supporting bar 19 (Fig. 5). The lower edge of the plate 48 has an integral base flange 51 which in turn has an up-

wardly extending tongue 52 which extends upwardly in the slot 25 or 26 (Figs. 5 and 6). The width of the flange 51 between the tongue 52 and the plate 48 is the same as the width of the cross piece 27 or 28 of the tube 19, so that the cross piece 27 or 28 will fit closely in the bracket to prevent axial play of the tube 19, and also to seat squarely on the flange 51. (Fig. 6). The upper corners of the tongue 52 may be chamfered to facilitate the entry of the tongue in the slot 25 or 26 when the supporting bar or tube 19 is mounted in place. By reason of the tongues 52 being close to the edge of the cross piece 27 or 28, any tendency of the tube 19 moving linearly is prevented.

When the blind is to be mounted outside of the window frame, the type of bracket shown in Fig. 12 may be used. This bracket comprises a plate 48^a having an integral right angle plate 48^b having screw holes 50^a for receiving screws for securing the plate firmly to the outer facings of the window frame. Both plates 48^a and 48^b have integral reinforcing flanges 51^a and 51^b of which flange 51^a has an upstanding tongue 52^a designed to perform the same function as tongue 52 of the bracket shown in Fig. 11. With the tube 19 mounted in place on these brackets (Fig. 12), it will be apparent that should the tube 19 move linearly it will be impossible for either end of the tube 19 slipping out of place, the tongue 52^a projecting up through the opening 25 or 26 and engaging the edge of the cross piece 27 or 28, preventing this to happen. In other words, the tongues 52^a, as also 52, lock the tube in place so far as horizontal movement of the tube 19 is concerned.

The means for contracting and for permitting the extension of the blind comprises ropes so connected to the sections as to effect successive contracting or extension of the sections of the blind. In the two section blind (see Fig. 4) rope 55 has an end 55^a thereof connected (at the left) to the lowermost slat 7^a of the first or upper section of the blind, and its other end 55^b connected (at the left) to the lower slat 8 of the second or lower section of the blind. The other rope 56 has an end 56^a connected (at the right) to the lower slat 7^a of the first or upper section of the blind, and its other end 56^b connected (at the right) to the lower slat 8 of the second or lower section of the blind. Both ropes are looped so that their looped portions 55^c and 56^c pass around a pulley 57 rotatably carried by a handle 58. In other words the rope 55 runs from connection 55^a of slat 7^a to and over tube 36, thence to tube 31, thence to loop 55^c, thence to tube 31 (second rope as shown in Fig. 4), thence to connection 55^b of slat 8. Similarly rope 56 runs from connection 56^a of slat 7^a to and over tube 35, thence to tube 31 (third rope shown in Fig. 4), then to loop 56^c, thence to tube 31 (fourth rope shown in Fig. 4), thence to tube 35, and thence to connection 56^b of slat 8. From this it will be apparent that when handle 58 is pulled downwardly, both ropes will move in unison because of the pull of the pulley 57 on the loops 55^c and 56^c. The pull, being effected on both rope portions 55^a and 56^a, will raise the bottom slat 7^a of the upper section successively piling up these slats of this section. As the bottom slat 7^a of the upper section is connected to the suspension tapes 11 and 12, that slat accordingly lifts the lower section which remains in extended condition, that is, the slats of the lower section remain in spaced relation. The pull of the pulley 57 on the loops is such as to take up the rope portions running to the lower slat 8 as it is raised with the other slats of the

lower section. Fig. 2 shows the position of the slats after partial contraction of the upper section. Fig. 3 shows the position of the parts after the upper section has been completely contracted, 5 and after the lower section has started to contract.

When the upper section is completely contracted, the rope portions running from the slat 7^a to the loops 55^c and 56^c, cease to continue movement, 10 but continued pull on the loops by the pulley 57 causes the rope portions extending from the loops to the slat 8 to move thus causing an upward pull on the slat 8 and the piling up of the slats in the lower section. See Fig. 3 for showing this 15 after partial piling up of the lower slats of the lower section. In Fig. 2 the dotted line position shows the full extended position of the blind and in Fig. 3 the lower dotted line position shows the half raised position of the lower section, and 20 the upper dotted line position shows the full contracted position of both sections of the blind.

In Figs. 13 and 14 is shown a three section blind. In this case rope 60 runs from slat 7^b (left end) by way of tubes 36 and 37 to a loop over pulley 57^a, thence to and over tubes 37 and 36 to slat 7^c, and similarly rope 61 runs from slat 7^b to and over tubes 35 and 37, thence to loop over pulley 57^a, thence to and over tubes 37 and 35, and thence to slat 7^c. So far this is the same as shown in Fig. 4. To operate the lower slat 8^a, another rope 62 is looped through a ring 63 connected to the case of pulley 57^a, and the two laps of the rope 62 pass around pulley 57^b and thence to and over tube 37, one of the laps passing over tube 36 and thence to the slat 8^a, and the other of the laps passing over tube 35 and thence to slat 8^a. In operation a pull on the handle 58^a first causes all the rope laps to move in unison, the slats 7^b of the first section piling up, and the 40 other sections rising in extended condition, until all the slats 7^b of the first section are piled or packed. Then the ropes connected to the slats 7^c and 8^a move in unison, the slats 7^c of the second section piling up while the third section rises 45 in extended condition until all the slats 7^c of the second section are piled up, then the rope laps of rope 62, only, move to pile up the slats of the third section.

By following the same system and compound- 50 ing the pulley arrangement (57^a—57^b), the blinds may be made to contract in any number of sections.

The slats 7 are provided with elongated slots 70 to permit the passage of the ropes when the 55 slats are either in horizontal or inclined positions. At the slat 7^a (and also 7^b in the three section blind) the ends of the ropes 55 and 56 are secured to cleats 71 and 72 shown more specifically in Fig. 10. Each cleat has a body portion 60 73 provided with holes 74 and 75 through which pass the ropes 56 and 55, and a clip portion 76 made by bent over laterally extending portions. As shown in Figs. 7, 8 and 9, the end of rope 55 65 passes through the hole 75 and is clamped in the clip portion 76. At the right hand end of the blind (Figs. 4 and 6) the end portion of rope 56 passes through the hole 75 of that cleat and is clamped in the clip portion 76. The companion rope 56 or 55 as the case may be, passes through 70 the hole 74 and through the slots of the slats of the lower section, and has its end connected to a knob or ball 77 located in a recess 78 formed in the lower slat 8. The suspension tapes may be secured to the lower slat by suitable means, as 75 tacks or the like 79 (Figs. 6 and 7).

The cleat bears upwardly in simple contact with the under face of the slat 7^a (Figs. 6, 7, 8 and 9) and is capable of sliding crosswise of the slat as the slat is tilted so as to accommodate itself to central position when the slat is tilted and as the ropes pull thereon and therethrough when operating the blind. 5

Since the slat 7^a is designed to raise the lower section by way of the suspension tapes, extra cross tapes 80 are located above the slat 7^a (Fig. 6) 10 and are secured at their ends to the suspension tapes. When the slat 7^a rises it lifts through the cross tapes 80 and the suspension tapes.

The handle 58 or 58^a may have means as a ring or hook 81 (Fig. 1) adapted to be engaged with any one of any number of hooks provided as desired on the jamb 2 (Fig. 1). The handle may also be weighted if desired, its weight being such as to counter-balance the weight of the slats. 15

In Figs. 15 and 16 are shown in schematic perspective, blinds with rope systems so connected and arranged that there is a looped rope for each section so that each section may be independently controlled by a looped rope. 20

As shown in Figs. 15 and 16 the lower slats 7^d, 7^e, and 8^d of the first, second and third sections respectively are connected respectively to the two ends, 81, 82 and 83 of the looped ropes 84, 85 and 86 so that a pull on the looped rope 84 will lift the slat 7^d; rope 85 will lift slat 7^e, 30 and rope 86 will lift slat 8^d. The rope ends 81 and 82 are respectively connected to cleats 72^a and 72^b beneath the slats 7^d and 7^e, and the rope ends 83 are connected to suitable means as knobs or knots beneath the slat 8^d. The cleats 72^a and 72^b are provided with suitable holes for the passage of the rope parts or segments running to the slats 7^d, 7^e and 8^d. 35

In Fig. 15 the rope 84 has a loop 87 with which is interlooped a loop 88 of rope 85, and in turn rope 86 has a loop 89 looping over a bend 90 of the rope 85, the latter having a bend 91. 40

In operation, (Fig. 15), to lift the blind and to contract the upper section only, all three ropes 84, 85 and 86 are pulled together. Slats 7^d pack 45 up and the second and third sections are lifted with the slats thereof in spaced relation. See dotted line position of slats 7^d for fully packed or piled up position.

When slats 7^d are fully packed up, further 50 movement of the rope 84 ceases. The loop 87 may then be hooked under a pin 92 fixed in the side jamb of the window frame so as to hold the slats 7^d in packed up condition.

Further pull may then be on ropes 85 and 86 55 together such that the bend 90 slides through loop 89 and lengthens out as shown in dotted lines in the lower left hand portion of Fig. 5. Slats 7^e will then be packed up as shown in dotted lines in the upper part of Fig. 15. The bend 90^a may 60 then be hooked under a pin 93 fixed in the side jamb of the window frame.

Further pull may then be on rope 86 only, the bend 91 lengthening out as shown in dotted lines in the lower left hand portion of Fig. 15. This bend 91^a may then be hooked under a pin 94 65 fixed to the side jamb of the window frame. In this case the slats 8^d will be packed up as shown in dotted lines in the upper part of Fig. 15.

The pulls above mentioned may be effected by 70 placing the fingers of the hand in the loop 87, and the bends 90 and 91. After hooking loop 87 under pin 92, then the fingers in bends 90 and 91 effect the pull on ropes 85 and 86, the rope 85 sliding around the finger in the bend 90 to 75

lengthen out that bend, and later the rope 86 sliding around the finger in the bend 91 to lengthen out that bend. On the other hand pulleys may be located in the loop 87 and bends 90 and 91 similarly to the pulley system shown in Fig. 13. While three sections are shown for illustration it will be understood that the same system may be carried out as disclosed for a blind having any desired number of sections.

10 In Fig. 16 the ropes 84, 85 and 86 have their loops 95, 96 and 97 independent from each other and to them are connected pull cords 88, 89 and 100 respectively. The pull cords may be pulled together or independently as desired. The cords 15 98, 99 and 100 have loops or the like 101, 102 and 103 for hooking under pins 92, 93, and 94 shown in Fig. 15. The operation is believed to be obvious.

In Figs. 17 and 18 are shown alternate forms 20 of brackets for supporting the head bar 19^a corresponding to the bar 19 in Figs. 5 and 6. To one of the side jamb stops, such as stop 4, is secured a plate 104 by means of screws 105. This plate has a lateral extension 106 capable of extending into the hollow member 19^a (as shown) 25 for a sufficient distance to act as a supporting ledge or the like for the end portion 19^b of the member 19^a, the end 19^c of the member 19^a abutting the surface of the plate 104.

30 At the other end of the supporting bar or head support 19^a is provided a spring bracket comprising a plate having a base portion 107 secured to the stop 3 by screws 108, and a spring portion 109 having a laterally extending flange or ledge 110 adapted to be located beneath the end portion 19^d for supporting the same on the ledge 110. The ledge 110 has an upwardly extending flange 111 adapted to resiliently press against the end portion 19^d of the bar 19^a so as to maintain the 40 other end 19^b in place on the ledge 106, the part 111 projecting up through a slot 112 provided in the upper wall of the bar 19^a and at the end thereof as clearly shown in Figs. 17 and 18.

When assembling the bar 19^a and the blind 45 supported by it, the end (right hand end as viewed in Figs. 17 and 18) is pressed against the spring part 109—111 toward the stop 3 to such an extent as is necessary for the other end portion 19^b to clear and be located above the 50 ledge 106, and then the spring portion 109—111 moves the bar 19^a so that its end 19^c abuts the plate 104 and the end portion 19^b rests upon the ledge 106, the other end portion 19^d then resting on ledge 110 and being abutted by the spring 55 part 111, as shown in Fig. 18. To remove the opposite operation is followed.

While I have herein disclosed a few illustrative embodiments of the invention, it is to be understood that the invention is not limited thereto but comprehends other constructions, arrangements of parts, details, features, and the like without departing from the spirit of the invention.

60 65 Having thus disclosed the invention, I claim:

1. A Venetian blind comprising a series of slats normally supported in spaced relation and arranged into upper and lower connected sections, and common means connected to said series of slats to cause a contraction or to permit an extension of said series by sections.

70 75 75 A Venetian blind comprising a series of slats normally supported in spaced relation and arranged into upper and lower connected sections, and common means connected to different sec-

tional parts of said series to cause a contraction or to permit an extension of said sectional parts in succession.

80 85 5 3. A Venetian blind comprising a series of slats normally supported in spaced relation and divided into a plurality of sections, and common means connected to said sections for successively causing a contraction or permitting an extension of said sections.

90 10 4. A Venetian blind comprising a series of slats normally supported in spaced relation and divided into a plurality of sections, and manually operative common means connected to said sections to contract or permit extension of said sections successively.

15 15 20 5. A Venetian blind comprising a series of slats normally supported in spaced relation and divided into a plurality of sections, common means for contracting and extending said series by sections and comprising a plurality of members connected to said sections to contract or permit extension of a section while another section remains in extended or contracted condition.

25 25 30 6. A Venetian blind comprising a series of slats normally supported in spaced relation and divided into a plurality of sections, common means carried by the support and connected to said sections to contract a section while moving another section in extended condition, and to permit extension of a section while holding another section in contracted condition.

35 40 45 7. A Venetian blind comprising a series of slats normally supported in spaced relation and arranged into upper and lower sections, common means carried by the support and connected to the lower slats of the sections to contract the upper section while raising the lower section in extended condition, and to permit lowering of the lower section while holding the upper section in contracted condition.

50 50 45 8. A Venetian blind comprising a series of slats normally supported in spaced relation and arranged into upper and lower sections, common means carried by the support and connected to the lower slats of the sections to contract the upper and lower sections successively, and to permit extension of the lower and upper sections successively.

55 55 55 9. A Venetian blind comprising a series of slats normally supported in spaced relation and arranged into upper and lower sections, guides carried by the support, flexible operating elements extending over said guides and each having its ends connected severally to the lower slats of said sections, said elements acting to contract the upper section while raising the lower section in extended condition and to permit extension of the lower section while holding the upper section in contracted condition.

60 60 65 10. A Venetian blind comprising a series of slats normally supported in spaced relation and arranged into upper and lower sections, guides carried by the support, operating flexible elements in loop arrangement and extending over said guides and each having its free end secured to the lower slats of said sections, a manual means slidably connected to the loop portions of said elements, said elements acting to contract said upper and lower sections successively when said manual means is moved downward.

70 70 75 11. A Venetian blind comprising a series of slats normally supported in spaced relation and arranged into upper and lower sections, flexible elements for operating said sections and each element having an end thereof connected to the 75

lower slat of the upper section and the other end thereof connected to the lower slat of the lower section, and manual means slidably connected to an intermediate portion of each of said elements 5 for contracting said upper and lower sections respectively successively.

12. A Venetian blind comprising a series of slats including a lifting slat normally supported in spaced relation and arranged to be contracted or extended as desired, means including a cleat for contracting or extending the same, said means comprising manually operable elements each connected to said cleat disposed transversely beneath said lifting slat of the series, said cleat being slidably in contact with the under side of said lifting slat for accommodation for the tilted positioning of the slats.

13. In a Venetian blind having tiltable slats provided with slots, a connecting means for a lifting element passing through a slot comprising a cleat connected to the end of the element and disposed transversely of the slotted portion of the slat and slidably in contact with the under surface of said portion, said cleat accommodat- 25 ingly sliding when the slat is tilted.

14. In a Venetian blind having a series of slats and suspending means therefor, a support being polygonal in cross section, means for connecting the support to a window frame, a cylindrical member rotatably mounted on the corners of said support, said suspending means being connected to said member, said member being angularly movable for tilting said slats.

15. In a Venetian blind having a series of slats and suspending means therefor, a support being polygonal in cross section, means for connecting the support to a window frame, a hollow cylindrical member surrounding said support and angularly moveable thereon, said suspending

means being connected to said member, said said member being angularly movable for tilting said slats.

16. In a Venetian blind having a series of slats and suspending means therefor, a support means for connecting the support to a window frame, said support being polygonal in cross section, a hollow cylindrical member surrounding said support and having frictional contact with the corners of said support, said suspending means being connected to said member, said member being angularly movable for tilting said slats. 5

17. In a Venetian blind having a series of slats and suspending means therefor and flexible means for contracting and extending the blind, a support being polygonal in cross section, means for connecting said support to a window frame, said support being in the form of a hollow tube of polygonal cross section and having openings in its lower wall for the passage of said flexible means, and guide elements within said support and so located as to guide the flexible means passing through said openings. 10

18. In a Venetian blind having a series of slats and suspending means therefor, and flexible means for contracting and extending the blind, a support having means for connection to a window frame, said support being in the form of a rectangular tube and having openings in its lower wall for the passage of said flexible means, and guide elements in the form of tubes located within said support and having their ends connected to the side walls of said support, said guide elements being so located as to guide said flexible means through said opening and in said support. 20 25

CERTIFICATE OF CORRECTION.

Patent No. 2,075,462.

March 30, 1937.

BERT N. PARMENTER.

It is hereby certified that error appears in the printed specification of the above numbered patent requiring correction as follows: Page 5, second column, line 2, claim 15, strike out the word "said"; line 15, claim 17, for "thereof" read therefor; and that the said Letters Patent should be read with these corrections therein that the same may conform to the record of the case in the Patent Office.

Signed and sealed this 25th day of May, A. D. 1937.

Henry Van Arsdale
Acting Commissioner of Patents.

lower slat of the upper section and the other end thereof connected to the lower slat of the lower section, and manual means slidably connected to an intermediate portion of each of said elements 5 for contracting said upper and lower sections respectively successively.

12. A Venetian blind comprising a series of slats including a lifting slat normally supported in spaced relation and arranged to be contracted or extended as desired, means including a cleat for contracting or extending the same, said means comprising manually operable elements each connected to said cleat disposed transversely beneath said lifting slat of the series, said cleat being slidably in contact with the under side of said lifting slat for accommodation for the tilted positioning of the slats.

13. In a Venetian blind having tiltable slats provided with slots, a connecting means for a lifting element passing through a slot comprising a cleat connected to the end of the element and disposed transversely of the slotted portion of the slat and slidably in contact with the under surface of said portion, said cleat accommodat- 25 ingly sliding when the slat is tilted.

14. In a Venetian blind having a series of slats and suspending means therefor, a support being polygonal in cross section, means for connecting the support to a window frame, a cylindrical member rotatably mounted on the corners of said support, said suspending means being connected to said member, said member being angularly movable for tilting said slats.

15. In a Venetian blind having a series of slats and suspending means therefor, a support being polygonal in cross section, means for connecting the support to a window frame, a hollow cylindrical member surrounding said support and angularly moveable thereon, said suspending

means being connected to said member, said said member being angularly movable for tilting said slats.

16. In a Venetian blind having a series of slats and suspending means therefor, a support means for connecting the support to a window frame, said support being polygonal in cross section, a hollow cylindrical member surrounding said support and having frictional contact with the corners of said support, said suspending means being connected to said member, said member being angularly movable for tilting said slats. 5

17. In a Venetian blind having a series of slats and suspending means therefor and flexible means for contracting and extending the blind, a support being polygonal in cross section, means for connecting said support to a window frame, said support being in the form of a hollow tube of polygonal cross section and having openings in its lower wall for the passage of said flexible means, and guide elements within said support and so located as to guide the flexible means passing through said openings. 10

18. In a Venetian blind having a series of slats and suspending means therefor, and flexible means for contracting and extending the blind, a support having means for connection to a window frame, said support being in the form of a rectangular tube and having openings in its lower wall for the passage of said flexible means, and guide elements in the form of tubes located within said support and having their ends connected to the side walls of said support, said guide elements being so located as to guide said flexible means through said opening and in said support. 20 25
